OUTBOARD MOTOR SAFETY HITCH

Arthur Basil Price, Moosomin, Saskatchewan, Canada

Filed Oct. 2, 1959, Ser. No. 844,136

4 Claims. (Cl. 248—25)

This invention relates to motor boats and more particularly to a safety hitch for outboard motors.

It is an object of the present invention to provide an outboard motor safety hitch which will prevent the outboard motor from leaving the motor supported transom of the boat, to thus prevent damage and loss.

Another object of the present invention is to provide a safety hitch for securing an outboard motor to a motor boat transom which will secure the motor in place and prevent disengagement thereof from the transom.

Still an additional object of the present invention is to provide an outboard motor safety hitch of the above type which can be readily applied and removed and which can be adapted for use with all types of motors and motor boats.

Other objects of the invention are to provide an outboard motor safety hitch bearing the above objects in mind which is of simple construction, has a minimum number of parts, is inexpensive to manufacture and efficient in operation.

For other objects and for a better understanding of the invention, reference may be had to the following detailed description taken in conjunction with the accompanying drawing, in which:

FIGURE 1 is a front plan view of an outboard motor safety hitch assembly made in accordance with the present invention in actual use;

FIGURE 2 is a side view of the safety hitch assembly shown in FIGURE 1;

FIGURE 3 is a plan view of a mounting member forming a part of the present invention;

FIGURE 4 is a view similar to FIGURE 3, of another mounting member;

FIGURE 5 is a plan view of a main mounting bar forming another part of the present invention;

FIGURE 6 is a plan view of a cross bar forming another part of the present invention;

FIGURE 7 is a plan view of a screw eye forming another part of the present invention;

FIGURE 8 is a plan view of a tensioning device of the present invention;

FIGURE 9 is a plan view of a flexible cable forming still another part of the present invention; and

FIGURE 10 is a plan view of an anchor member for securing the cable to the screw eye in accordance with the present invention.

Referring now more in detail to the drawing, an outboard motor safety hitch assembly 10 made in accordance with the present invention is shown to include a main mounting bar 12 having a central opening 14 through which a cross bar 15 extends. The main mounting bar 12 also has an opening 16 extending through the upper end thereof through which a flexible cable 18 is slidably received. The lowermost end of the main mounting bar 12 is also provided with a transverse bore 20 that supports the central portion of a bail member 22 having guideways 24 which receive the mid portions of the cable 18 and guide them toward secured engagement with the outwardly extending lugs 26 of a cable anchor member 28. The cable extends through the central opening of a screw eye member 30 that is attached to the transom 32 of the boat and is secured to the cable anchor member 28. Thus, the free ends of the cable 18 carried upon the lugs 26 of the

2

clamp 28 are effectively locked in assembly with the screws eye 30 by the engagement of the lugs 26 with the screw eye.

Each end of the cross bar 15 is provided with a transverse bore 34 which pivotally supports a pair of mounting hooks 36, the ends of which are bent at right angles, passed through bore 34 and riveted, allowing movement of the hook in either direction to accommodate motor tightening bolts of different widths and also to enable one to remove hooks from the thumb screws of the motor.

10 When the motor is applied to the transom board 33, as shown in FIGURE 2 of the drawing, the engagement of the hooks 36 with the motor bracket and the securement of the cable 18 to the screw eye 30, thus prevents upward movement of the motor relative to the transom board 33, 15 thus preventing the motor from becoming dislodged from the boat. The cable 18 is maintained in tension by extending it behind the cross bar 15 and forwardly over the guide portions 24 of the bail member 22. However, this tension can be released simply by disengaging the cable from the 20 bail member 22, following which the upper end of the main mounting bar will tilt downward toward the transom thus reducing tension on the cable and the hooks can be lifted from the motor mounting bracket 38, to allow the motor to be removed whenever desired.

25 While various changes may be made in the detail construction, it shall be understood that such changes shall be within the spirit and scope of the present invention as defined by the appended claims.

What I claim as new and desire to protect by Letters 30 Patent of the United States is:

1. An outboard motor safety hitch comprising, in combination, a main mounting bar comprising an elongated rigid rod having a central transverse opening and transverse openings parallel to each other and said central 35 opening at each end thereof, a cross bar slidably extending transversely through said central opening of said main mounting bar, mounting means for attaching said cross bar to mounting clamps of an outboard motor, securement means for attaching said main mounting bar to the 40 motor supporting transom of a boat, said securement means comprising a flexible cable slidably extending through said one end opening of said main mounting bar, and anchor means attaching the opposite free ends of said flexible cable to the transom of the boat and tensioning means extended through said other end opening of 45 said mounting bar for tightening said cable and preventing rotation of said mounting bar about said cross bar.

2. The combination according to claim 1, wherein said mounting means comprises a pair of hooks one secured to 50 each end of said cross bar for supported engagement upon the mounting brackets of the motor.

3. The combination according to claim 2, wherein said anchor means comprises an anchor member secured to 55 said opposite free ends of said flexible cable, and a screw eye carried by the transom of the boat slidably receiving the mid sections of said opposite ends of said flexible cable therethrough and releasably preventing outward movement of said anchor block therethrough.

4. The combination according to claim 3, wherein said 60 tensioning means comprises a bail member having guide means slidably receiving the mid sections of the ends of said flexible cable.
